O. P. CRAMER.
SUSPENSION DEVICE FOR GLOBES AND REFLECTORS FOR INDIRECT AND CONCENTRATED LIGHTING.
APPLICATION FILED JULY 5, 1921.

1,414,627.

Patented May 2, 1922.

Inventor.
Otto Paul Cramer.
By Henry P. Stoy atty.

UNITED STATES PATENT OFFICE.

OTTO PAUL CRAMER, OF GENEVA, SWITZERLAND.

SUSPENSION DEVICE FOR GLOBES AND REFLECTORS FOR INDIRECT AND CONCENTRATED LIGHTING.

1,414,627.

Specification of Letters Patent. Patented May 2, 1922.

Application filed July 5, 1921. Serial No. 482,512.

To all whom it may concern:

Be it known that OTTO PAUL CRAMER, engineer, citizen of Germany, residing in Geneva, Switzerland, and whose post-office address is 118 Rue des Eaux-Vives, has invented certain new and useful Improvements in Suspension Devices for Globes and Reflectors for Indirect and Concentrated Lighting; and he does hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In order to obtain an efficient distribution of the light of a lamp, it is found advantageous to suspend under the lamp shade either an entire or partial globe if it is desired to obtain an upward diffusion of the light or what is termed indirect lighting, or in other cases a second reflector where 25 the object is to obtain a concentration of the light in the downward direction.

The suspension device according to my invention consists in the use of supporting members in the form of portions of a circle 30 constituting the elastic hook coupling members used to secure the lower globe or reflector. Where elastic coupling hooks in the form of spring clamps are employed, these latter will constitute a clamp wherein the 35 edge of the globe is tightly held, and the said clamps are suspended at the desired height from the flanged collar of the lamp shade, or from the lamp holder, by means of chains.

40 The accompanying drawings show various embodiments of my invention.

Fig. 1 is a perspective view of a clamp in sheet steel, a plurality of the same being employed for the same purpose as a circular support. Fig. 2 shows the same clamp mounted upon a reflector, and Fig. 3 shows a modified form of the clamp in steel wire. Fig. 4 represents the entire suspension device for a reflector, employing the said 50 clamps. Fig. 5 shows a modified form of hook connection wherein the chains are replaced by cords provided with glass beads.

In the form of construction shown, the complete support is constituted by elastic 55 clamps or fasteners. Such clamps, Fig.

1, which are made of sheet steel, are punched and bent into shape in such manner that the inner portion a of the clamp shall be longer than the two outer portions a^1 . The curved portion of a is fitted into the 60 flaring part of the globe h in order to hold the latter firmly and to avoid all slipping, Fig. 2. The said clamp is also provided with a small tongue or hook a^2 for coupling with the chain b . It is also observed in 65 Fig. 2, that the suspension chain b draws upon the said hook in a direction which forms an angle of about 60° with the center line of the clamp, in such manner that the traction of the chain will act still further 70 to press the clamp against the edge of the globe h , thus affording great safety for this connection.

Fig. 3 shows a clamp which is constructed on the same principle as that of Fig. 1, but 75 is here made of steel wires bent in such manner as to obtain the same advantages.

For the suspension of the globe h the chains b may be replaced by cords b^1 , Fig. 5, provided with small glass beads, balls or 80 knots, and in this case the clamp is provided with a fork portion a^3 instead of a simple hook. The suspension of the globe is here obtained by inserting the said cord in the fork portion a^3 between any two of 85 the beads and at the desired height.

In Figs. 4 the chains b are provided at the upper end with hooks e . These hooks e may be given a suitable shape for engaging the three branches f^2 of the metal shade 90 holder to which the reflector is usually secured by three screws, as shown in Fig. 4.

Having now described and ascertained the nature of my said invention and in what manner the same is to be performed, I declare that what I claim is:

1. A suspension device for globes and reflectors for indirect and concentrated lighting, comprising portions of a circular support formed of sheet steel and bent in 100 such a manner as to constitute spring clamps fitting tightly upon the globe, a double hook of fork shape forming part of the said clamps, cords provided with beads adapted to engage the double hooks of the said 105 clamps, and upper hooks for suspending the globes and reflectors from the shade holder of the upper reflector.

2. A suspension device comprising a body portion having a pair of extensions spaced 110

apart at the end thereof, said extensions being shorter than the body portion, and a shorter extension between the aforesaid extensions, all of said extensions being bent 5 over toward said body portion.

3. A suspension device comprising a body portion having a pair of extensions spaced apart at the end thereof, said extensions being shorter than the body portion, and a 10 pair of shorter spaced extensions between the aforesaid extensions, all of said extensions being bent over toward said body portion.

4. In a suspension device of the character 15 described the combination of a beaded sup-

porting member, a clamp formed of spring metal comprising a body portion having a pair of parallel extensions spaced apart at the end thereof and bent back in parallel relation to said body portion, and a pair 20 of shorter parallel spaced extensions extending between the aforesaid extensions adapted to embrace the beads of the supporting member.

In testimony that I claim the foregoing 25 as my invention, I have signed my name.

OTTO PAUL CRAMER.
